UNITED STATES PATENT OFFICE.

EDGAR E. SALISBURY, OF CHICAGO, ILLINOIS.

SIGNAL SYSTEM.

Application filed January 24, 1925. Serial No. 4,547.

This invention relates to a signal system, and more particularly to a system of automatic control for patrolmen's movements, in which system is provided means for causing an automatic alarm at some selected station, as a police station, within a predetermined time, and in a predetermined order, after failure of the patrolman or patrolmen to properly operate any station box on his beat or route, and also upon any interruption to the circuit in which such boxes are placed.

To this end the principal object of my invention, broadly considered, is to provide a series of patrolmen's boxes designed and electrically connected in such manner that when operated in accordance with a pre-arranged schedule no record is made of the progress of the patrolman or patrolmen from station to station, or of the time or times any one or more patrolmen report at the several stations; but when not operated in accordance with the schedule, will automatically give an alarm or cause a signal to appear in a central station.

Another broad object of my invention is to provide a means, in such a system, to give an alarm or signal upon any interruption to or closing of the circuit in which such boxes are placed, depending upon whether a closed or open circuit is used.

Another object of my invention is to provide a station box and automatic supervisor for a system of the kind referred to, each of which is a unitary mechanism and, consequently, which may be shipped ready assembled without chance of loss or displacement of the component parts thereof.

A further object of my invention is to provide a series of electrically connected station boxes in which only one or more selected boxes may be operated at the same time.

Still another object of my invention is to provide an automatic supervisor for such a system comprising an electro-mechanical attachment for an ordinary clock movement, and constructed in such manner that it will not cause an alarm or give a signal when the system is functioning normally and properly operated.

There are many other objects of the invention which will appear from the following more detailed description thereof when considered in connection with the accompanying drawings which have been chosen to illustrate the same, and in which:

Fig. 1 is a schematic view of the system, showing diagrammatically the details of structure of the automatic supervisor;

Fig. 2 is a front elevation of a station box designed for use on a closed circuit with the cover removed, showing a part of the internal mechanism in elevation and set in operative position for a patrolman's visit;

Fig. 3 is a section taken along the line 3—3 of Fig. 2;

Fig. 4 is an end elevation of the box illustrated in Fig. 2;

Fig. 5 is a view similar to Fig. 2, but showing a station box designed for use on an open circuit;

Fig. 6 is a side elevation of the box illustrated in Fig. 5;

Fig. 7 is an end elevation of the box illustrated in Fig. 5;

Fig. 8 is a side elevation of the pulley mechanism of the supervisor;

Fig. 9 is a wiring diagram illustrating the manner of connecting a series of open circuit patrolmen's boxes in an open circuit.

It is desirable for public authorities, owners of factories and large office buildings, and other persons who employ patrolmen or watchmen, to determine whether or not the latter are performing their duties, and many mechanical and electrical systems have been devised with this end in view. In all of them, however, in so far as applicant is aware, it is necessary for the watchman to turn in an alarm at some central station from different points or stations on his route. When such an alarm is turned in, a record of that fact is made, together with the time it is received, and in this way the progress of the watchman or patrolman from station to station is checked.

The present invention obviates the necessity of checking patrolmen at a central station when they are functioning efficiently and while the system is in good working order. In a general way this object is attained by providing station route boxes of a novel design at specified locations on the street or throughout a factory, for example, and having the patrolman operate the same in a predetermined order in accordance with a time schedule. If the boxes are operated in accordance with such schedule no alarm or signal of any kind is made. On the other hand, if the patrolman neglects or fails to operate any box on time, or if for any reason

the device gets out of order, as when a line becomes broken, an alarm or signal will automatically be turned in at the central station through the medium of what may be called an automatic supervisor, which is electrically connected in the system, whereupon an appropriate investigation may be made.

With these purposes and objects in mind I have conceived and devised the structural details and arrangement of parts illustrated by the accompanying drawings. Referring now to such drawings, and particularly to the details of structure and arrangement of parts thereof by reference characters or numerals, in which like characters or numerals designate like parts, and more especially to Fig. 1 thereof, the reference character A designates patrolmen's route station boxes (three being shown) electrically connected by wires B, through a source of electrical energy D, to an automatic supervisor E, the system being grounded at Y. Two signaling devices M, as electric bells, are connected to the supervisor through a source of electrical energy b, as by wires a, and such bells are grounded at X.

I have illustrated two types of station boxes A, one designed for use on an open circuit and the other on a closed circuit. Either may be used as desired or when local conditions require.

The closed circuit box illustrated by Figs. 2 and 3 is the same in construction as all boxes used in a closed circuit system. This box consists of a case 1 in which is mounted an electro-magnet 2 of ordinary construction. The cores of this magnet attract an armature 3, which is mounted on a flange 5 of a sliding plate 4, as by means of screws 6, although the armature and plate may be made integral if desired. The plate 4 is mounted in grooves on the outer ends of guides 8 and 8', which guides extend through and are fixed in the back of the case 1. For this purpose the plate is provided with slots 7, 7', engaging said grooves. A stud 9 is fixed in the back of the case 1 and extends through and beyond a slot 9' in the center of plate 4. Fixedly mounted in a groove 10 in the outer end of the said stud is a control pin wheel 22, the latter of which is spaced from the said plate 4 so as not to interfere with its movement, as will hereinafter appear.

Suitably mounted on the lower end of the plate 4, as by means of screws 15, is an angle release arm 16, the free end 17 of which extends upwardly along and spaced from the said plate, and such end is provided with a forwardly extending projection 18. An adjustable set-screw 19 is passed through a stud 21, fixed immediately under the sliding plate 4 for limiting the downward movement thereof.

The control pin wheel 22 above mentioned

is provided with a series of circumferentially arranged forwardly projecting equally spaced pins 25. This wheel is rotatably and fixedly mounted on the stud 9, in the groove 10, by any suitable means, as by a screw 11 and washer 12. The pins 25 are fixed in the periphery of the flange 26 of the control wheel 22, which wheel is provided with a hollow forwardly projecting annular flange 27, on which is fixedly mounted a disc 28.

Pawl 31 are mounted on the front side faces of the plate 4 to alternately engage the upper and lower pins 25 of the control wheel 22 for propelling the same upon reciprocation of the plate. This arrangement is known in the horological art as a pin-wheel escape movement, and may be replaced in the present invention by any other mechanical movement, whereby the control wheel 22 may be actuated by the sliding plate 4. For example, a toothed wheel may be substituted for the pin wheel 22 and engaged by the pawls 31.

A series of apertures 32 are drilled through and around the periphery of the disc 28, and detachable lifting pins 33 are inserted therein for a purpose to be presently stated. These apertures may or may not be equally spaced, as desired.

An angular lock lever 34 is pivotally mounted, as by means of pivot pin 38, in the case, in such manner that the end of one arm thereof may engage the pins 33. For this purpose such end is provided with a finger 35, having a cam surface which is adapted to slide over the said pins. The other arm of the lock lever is provided with a cam projection 36 intermediate its end and the pivot pin 38, and also with a projection 37 extending in the same direction as the said cam 36, and adapted to engage a forwardly extending projection 39 on an angular control lever 41, which will now be described.

The control lever 41 is pivoted on the pivot pin 42 in such manner that one arm thereof will extend under the disc 28 and through an opening in the side of the case 1 (in the construction shown in Fig. 2), and terminate inside of the case in the construction shown by Fig. 5. The other end, 43, of this lever is provided with a spring contact arm 44, which is mounted on an insulation 45, fixed on the said arm. Ordinarily, the control lever is held in a raised position by means of a spring 42a, coiled around the stud 42, and having the free end thereof passed under a lug 40 on the said lever.

A binding post 46 is positioned on the case 1, under the contact arm and electrically connected thereto by means of a coiled wire 47 and to the main circuit through the medium of the insulated wire 51. Adjacent the said post an adjustable screw 48, functioning as a contact post for the arm 44, is provided. This screw is electrically connected, by means

of a wire 48^a, to the coils of the electro-magnet 2, which magnet is connected to the main circuit by means of the wire 52.

It will be noted from Fig. 1 of the drawings that an ordinary clock movement (not shown) actuates the automatic supervisor E through the medium of the shaft 54 and toothed wheel 55, the latter of which meshes with the teeth of a wheel 56, which is fixedly mounted on a shaft 57. A slip collar 58, provided with contact friction springs 59, 59', on the ends thereof, is splined on the shaft 57. This collar is provided at a point intermediate its ends with a groove in which a sliding yoke 61 is mounted.

There is also loosely mounted on the shaft 57, at the ends of the collar 58, two grooved pulleys 62, 62'. These pulleys are positioned by collars 63 fixed on the shaft. Each pulley is provided with a weight 66, which is connected thereto by means of a cord, flexible wire, chain, or other securing device 67, one end of the same being secured to the pulley. A tell-tale contact arm 68 is secured to each pulley in such position that a sufficient rotation of the same will bring the said arm into contact with a lug 69 on the end of and insulated from an arm 70, which arm is adjustably mounted on the shaft bearing. The lug 69 is electrically connected, through a source of electric energy b, by means of the wires a, to an ordinary electric bell or buzzer M, which is grounded at X, in the circuit selected to illustrate my invention.

The yoke 61, above mentioned, constitutes one end of a lever 71, which is pivoted, by means of a pin 72, intermediate its ends. One end of a link 73 is pivoted, by a pin 74, to the free end of the lever 71, the opposite end of said link being pivoted at 75 to the end of an armature 74' of an electro-magnet 76 in the main circuit of the system. The opposite end of the armature 74' is pivoted by means of a pin 77. Adjustable screws 750 are provided for holding the armature 74' in half-way or neutral position.

It will be understood that the parts of the devices herein disclosed are properly insulated wherever necessary, and that a suitable box or framework is provided for my supervisor, a specific description of the details of structure of the same being considered unnecessary for the purposes of this specification.

For the purpose of illustrating my invention a three-station route is disclosed. In operation of such a route the flexible cords 67 (Fig. 1) are unwound and the tell-tale contact arms 68 adjusted with respect to the arms 69. The pulley 62 is rotated to a position such that the said arm 68 will rotate to a point adjacent but not touching the contact lug 69, and then return to normal position through the automatic reversal of the pulley

when the station boxes are operated at the proper time.

To effect this result we may suppose that the boxes are set for operation at one hour intervals in the order they appear in the circuit, although they may be set for operation at any interval of time and need not be operated in the order above stated, and that the first box is to be operated at two o'clock. At one o'clock, for example, which will be indicated by the clock mechanism (not shown) connected to the shaft 54, the cord 67 (left-hand side of Fig. 1) is unwound, as illustrated, and the movable contact lug 69 and pulley 62 are set as shown by Fig. 1, and the contact friction spring 59 on the splined collar 58 is caused to engage the said pulley, the friction spring 59' on the opposite end of said collar being out of contact with its corresponding pulley.

Thereupon movement of the clock mechanism begins, which causes the shaft 54 to rotate. The rotation of this shaft in turn rotates the gears 55, 56, shaft 57, collar 58, and pulley 62. As this pulley revolves it slowly winds up the cord 67, and raises the weight 66 and, at the same time, brings the contact arm 68 thereon in increasingly closer relation with the lug 69.

After an hour has passed, viz:—at two o'clock, for example, the first route box is operated; that is to say, the main line circuit is momentarily interrupted, as will later appear. Immediately upon the opening of the circuit the electro-magnet 76 is demagnetized, whereupon the spring 74^a raises the armature 74' and shifts the collar 58 through means of the link 73 and lever 71. Thereupon the weight 66 will drop by gravity, causing the cord 67 to be unwound and the contact arm 68 returned to normal or zero position.

In the event, however, that the first, or any other box in the system, is not operated on time, the armature 74 will be held in the position illustrated by Fig. 1, and the clock mechanism will bring the arm 68 into contact with the insulated lug 69 after a predetermined interval of time, say five minutes. Inasmuch as this lug is electrically connected to an electrical bell M, or other signaling device, located in a central station, it will be seen that an alarm or signal will then be given.

The pulley 62' is constructed and connected to a signaling device, as the one previously described. This pulley, however, is always out of contact with the spring 59' so long as the main circuit is unbroken. But should such circuit become interrupted for any reason, the armature 74' would be released through the demagnetization of the electro-magnet 76, whereupon the collar 58 would shift the said spring 59' into frictional engagement with the said pulley, and

the clock mechanism would cause the arm 68 thereon to contact with its corresponding lug after a predetermined time and thereby give an alarm, as previously described. When so shifted the contact spring 59 would be disengaged from the corresponding pulley.

If it be desired to hold the contact springs 59, 59', out of contact with both pulleys in order to permit the clock mechanism to operate without causing the supervisor to function, the screws 750 may be adjusted to hold the armature 74' in midway position, which in turn will shift the splined collar 58 in neutral position.

Further, I desire it to be understood that although I have described my automatic supervisor connected with an electric bell, it may be used to set in operation any signaling device regardless of whether or not the latter is connected in some other signaling system. For example, it may be employed in connection with a railway watch tower system and when so used the supervisor would be connected to the system as hereinbefore described and set off an alarm when the towerman did not operate an appropriate device to either make or break a circuit at predetermined times. Also, if desired, only one signaling device may be connected to the supervisor to indicate either an interruption to the circuit or upon failure of any one to operate a box. These changes lie within the skill of a mechanic, and description of the details of structure necessary to accomplish these changes are deemed unnecessary for present purposes.

Referring now to the open circuit box and system, it will be noted from an inspection of Fig. 5 that my open circuit station route box is the same in construction as the one previously described, except that the contact post 48 is electrically connected to the main circuit, as by means of a wire *g*, and that the projection 39 on the control lever extends through an opening in the front of the case 1 to serve as an operating handle, the ends of the lever 41 being on the inside of the box. In Fig. 9 I have shown the manner of connecting these boxes in an open circuit system. Normally the armatures 74' and 3 of the supervisor and route boxes are in open position. When any contact arm 44 of a box is brought into contact with its contact post, the circuit is closed through an electro-magnet 2, wire *e*, electro-magnet 76, and wires *d* and *h* back to the said electro-magnet. The magnetization of the electro-magnet 76 attracts the armature 74' and causes a signal to be given, as will be presently described.

Referring to the three-station route closed circuit box shown in Figs. 2 and 3, the first box is set as illustrated. That is to say, the armature 3 and sliding plate 4 being

raised and the cam face on one end of the finger 35 being in engagement with one of the lifting pins 33. These pins are inserted in every third hole so that two holes appear between each adjacent pair of pins in a three-station route system. In this position the cam face 36 on lock lever 34 is out of engagement with the projection 18 on the release arm 16.

A patrolman may now depress the projecting end of the operating lever, which demagnetizes the electro-magnet 2 by breaking the main circuit through the separation of the spring contact arm 44 and contact screw 48. Thereupon the sliding plate 4 drops through the force of gravity, which brings the upper pawl 31 into contact with a pin on the control wheel 22 and partially rotates the same. The rotation of this wheel causes the disc 23, mounted thereon, to also revolve and the cam face on the finger 35 to continue to ride on the pin 33 on said disc. Simultaneously therewith, the circuit being broken, the magnet 76 (Fig. 1) is demagnetized and the weight 66 (left-hand side of the figure) drops, as previously described. Upon releasing the control lever 41 the spring 42^a returns the same to normal position, closes the contact between the spring arm 44 and screw contact post 48, whereupon the electro-magnet 2 is remagnetized and attracts the armature 3 and thus causes the sliding plate 4 to rise. The upward movement of this plate causes the lowermost pawl 31 to engage another pin on the control wheel 22 and partially rotate the same. This further rotation of the wheel causes the disc to revolve and the cam face on the finger of lock lever 34 to ride completely over the pin 33, whereby the said finger drops behind the said pin and in front of the next adjacent hole and permits the projection on the end of said lever 34 to lock under the projection 39 on the control lever.

From what has been said it will be noted that a complete reciprocation of the plate 4 causes the cam face on the finger 35 to ride over and past a pin 33 when the mechanism is set as illustrated by Fig. 2 of the drawings. Two more complete reciprocations of the plate will bring the said cam surface into contact with the next adjacent pin when two holes are left between adjacent pairs of pins, as previously mentioned.

If the three-station route boxes are to be operated one after the other as they are placed in the line or circuit, the disc in the third station box will be set, just before the first box is operated, so that the finger 35 will be in front of a pin, and the finger in the second station box will be between two holes. Inasmuch as the depression of any one operating lever opens the circuit,

all of the magnets in all of the boxes will be simultaneously demagnetized. Consequently a depression and release of any operating lever will cause the simultaneous 5 operation of the mechanism in all boxes, which includes, of course, the simultaneous rotation of all discs.

The lifting pins in the discs being arranged and the mechanism in the boxes set 10 as specified, it will be seen that at the time the first box is to be operated the other two are locked by the interlocking of the projections 37 and 39. The complete operation of the first box locks itself, unlocks the second, and leaves the third locked; and the 15 operation of the second box locks itself, leaves the first locked, and unlocks the third, and so on for the number of boxes used in the system. Therefore, in any event the 20 said boxes must be operated in a predetermined order.

Although the foregoing description relates particularly to a closed circuit system, my invention may also be used in connection 25 with an open circuit by initially raising the armature 74' (Fig. 9) and setting the mechanism in all patrol boxes as illustrated by Fig. 5, and the discs as previously described, that is to say, with the spring contact arm 30 44 out of contact with the adjustable contact post 48, whereupon the magnets 2 will be demagnetized and the sliding plate 4 in lowered position.

In a system of this kind, viz: an open 35 circuit system, the contact friction spring 59' (Fig. 1) will ordinarily be in engagement with the pulley 62', and the signaling device associated therewith used to indicate the failure of a watchman to report at 40 and operate any box within a specified time after the time schedule, or upon failure of the box system for any reason. The other signaling device will be used to indicate a closing of the circuit by accidental or other 45 means. Otherwise the devices function and operate as the closed circuit mechanism described.

While I have shown my invention as used in connection with three-station route 50 boxes, and described the same as adapted to be operated in the order in which they are placed in the circuit, I desire it to be distinctly understood that this arrangement and use of the invention includes the use of 55 any number of such boxes and is not limited to the operation of the boxes in the order stated, since all boxes, and each of them, regardless of number, may be set for operation at any predetermined time or times. 60 It will further be understood that my automatic supervisor is adapted to set in operation any signaling mechanism, regardless of whether the latter is used in some other signaling system. For example, it may be 65 used to set in operation a device in an ordinary

police signal system to give an alarm or signal.

Also, it will be understood that although I have disclosed two specific embodiments of my invention, I do not intend to be limited by such embodiments or the specific mechanism described, except in so far as the same may be limited by the scope of the appended claims.

I claim as my invention:—

1. In a signaling system, a central station, a signal in said station, a plurality of patrol boxes, means for electrically connecting said boxes, and means for operating said signal within a predetermined time after the said connection becomes inoperative.

2. In a signaling system, a central station, signal means within said station, a plurality of patrol boxes, means for electrically connecting said boxes whereby they can be operated only in a predetermined order, and means for operating said signal at a predetermined time after said connection becomes inoperative.

3. In an electrical circuit, the combination 90 of a plurality of patrol boxes and a signal mechanism, said boxes comprising means for setting each box for operation within a predetermined time after the operation of the preceding box, means comprising a winding mechanism and an electro-magnet energized by the operation of said boxes for rendering the same inoperative to produce a signal when the said box is operated on time.

4. In an electrical circuit, the combination 100 of a plurality of patrol boxes and a signal mechanism, said boxes comprising means including discs having pins therein for setting the same for operation within different predetermined times and the said mechanism comprising means for rendering the same inoperative when the said boxes are operated on time.

5. In an electrical circuit, the combination 110 of a plurality of patrol boxes and a signal mechanism, the said boxes comprising means for setting the same for operation within different predetermined times and the said mechanism comprising means including weights and pulleys for rendering the same inoperative when the said boxes are operated on time.

6. In station patrol mechanism, the combination with an electro-magnet, of an armature, and means including winding mechanism, associated with said armature for automatically setting the said mechanism for operation within a predetermined time.

7. In a station patrol mechanism, the combination with an electro-magnet, of an armature, and means associated therewith for automatically setting said mechanism for operation within a predetermined time,

the said means including a disc having pins projecting laterally therefrom.

8. In a station patrol mechanism, the combination with an electro-magnet, of an armature on a sliding plate, and means associated with said armature for setting the same for operation within a predetermined time, the said means including a disc having pins projecting therefrom, and means for locking the said mechanism in inoperative position.

9. The combination in a station patrol mechanism, of an electro-magnet, an armature for said magnet, the said armature being on a sliding plate, a disc having pins projecting therefrom, means for operatively connecting the said plate and the said disc, a lever having a cam surface on one end thereof for riding over the said pins, and means for locking the said mechanism.

10. In a supervisor for a system of the kind herein disclosed, the combination with an electro-magnet, of a signaling device, and means including winding mechanism, associated with said device for normally rendering the same inoperative when said electro-magnet is energized.

11. In a signaling mechanism, the combination of a pulley having a flexible cord and contact arm thereon, a weight on said cord, a shaft for said pulley, a splined collar on said shaft for engaging said pulley, means including an electro-magnet associated with said collar for throwing the same into and out of engagement with said pulley, a signaling device, and electrical connections between said arm and device and for said means whereby the said mechanism is rendered operable.

12. A signal system comprising a plurality of patrol boxes and an automatic signaling device, electrical means connecting said boxes and device, and means whereby said boxes when operated must be operated in a predetermined order, but may be operated at any time within a predetermined

period after the operation of the preceding box.

13. In a signal system, an automatic signal device, supervisor mechanism for controlling the operation of said device, means for operating said device when said mechanism is not operated within a predetermined time after its preceding operation, a plurality of patrol boxes, means for operating said mechanism when any one of said boxes is operated, and means for preventing the operation of said boxes except in a predetermined order, but permitting any box to be operated at any time within a predetermined period after the operation of the preceding box for preventing the operation of said signal device.

14. In a signal system, a signal device, a plurality of patrol boxes, means for automatically operating said device when any one of said boxes is not operated within a predetermined time after the operation of the preceding box, and means for preventing the operation of said boxes except in a predetermined order, but permitting any box to be operated at any time within a predetermined period after the operation of the preceding box for preventing the operation of said signal device.

15. In a signal system, a signal device, supervisor mechanism adapted to be reset for preventing the operation of said device, a plurality of patrol boxes, means operated by the operation of any of said boxes for resetting said mechanism, means for preventing the operation of said boxes except in a predetermined order but permitting any box to be operated at any time after the operation of the preceding box, and means for operating said device when the supervisor is not reset after a predetermined time after the operation of the box last operated.

In testimony whereof I affix my signature.

EDGAR E. SALISBURY.

CERTIFICATE OF CORRECTION.

Patent No. 1,645,353.

Granted October 11, 1927, to

EDGAR E. SALISBURY.

It is hereby certified that error appears in the printed specification of the above numbered patent requiring correction as follows: Page 5, line 123, claim 6, after the word "said" insert the word "patrol"; and that the said Letters Patent should be read with this correction therein that the same may conform to the record of the case in the Patent Office.

Signed and sealed this 1st day of November, A. D. 1927.

Seal.

M. J. Moore,
Acting Commissioner of Patents.
